UNITED STATES PATENT OFFICE.

CYRUS W. SALADEE, OF WOLCOTTVILLE, CONNECTICUT.

ROAD-WAGON.

SPECIFICATION forming part of Letters Patent No. 240,464, dated April 19, 1881.

Application filed January 31, 1881. (No model.)

To all whom it may concern:

Be it known that I, CYRUS W. SALADEE, of Wolcottville, State of Connecticut, have invented certain Improvements in Road-Wagons, of which the following is a specification.

The first part of my invention relates to springs for supporting carriage bodies or platforms of any kind; and it consists of two flexion members, arranged one over the other, the upper member being attached directly or indirectly to the body or platform, and the lower member being connected to the upper and attached to the side bars or frame of the running-gear or other support, the upper and lower members being of such form that the bending or straightening of the lower member will alter the form of the upper to impart increased tension, thereby securing, under all pressures and in all positions, an extremely elastic support, and preserving the position of the body or platform, whether loaded centrally or at the side.

The other part of my invention relates to the mode of securing the end cross-pieces of a frame—as the side-bars in a road-wagon—to the rear axle and bolster thereof, and has for its object more secure, sightly, and simple attachment at these points.

In the drawings, Figure 1 is a diagram illustrating the first part of my invention. Fig. 2 represents, in perspective, the running-gear of a side-bar wagon, except the wheels and shafts, with my improvements. Fig. 3 represents a side or end elevation of a body, showing the manner of attaching thereto the improved spring-support. Fig. 4 represents a modification of my improved spring-support. Fig. 5 is a detached top view of the springs seen in Fig. 4. Fig. 6 is a perspective view, showing my improved connection; and Fig. 7 a perspective view of the clip.

The principle of my invention is best illustrated in the diagram 1, where B and C are the members of the spring, the member B being attached at one end to the body or other platform, A, and the member C being secured at its outer end to the frame or other support, E, and both being connected at their inner ends. The shape of the two members is not material, except that it should be such that as the member C is flattened or changed in form

under pressure it will act as a lever to depress the inner end or portion of the member B, while the two may be shaped so that the descent of the body will result in gradually increasing the bearing of the upper upon the lower member, thereby shortening the latter and imparting the increased stiffness necessary to support the increasing load. Thus in the construction shown in Fig. 1 any descent of the body A tends to flatten the member C, and the latter, bearing on the upper member at about the point x, acts as a lever to bend down the inner end of the member B, to which it is connected, both members being thus subjected to tension; but, owing to the different forms in different ways, the upper member, instead of being bent toward the body, as in ordinary springs, being bent from it. As the two members are pressed together the bearing of the upper upon the under is increased. The lower member is thus practically shortened, imparting an increased tension or stiffness, so that as the vehicle is loaded the strength or resistance of the spring will increase correspondingly. Thus when the load is light the members will be in contact from y to x; when loaded the contact will be from y to x'. Two or more such springs may be combined; but in practice I prefer to use the arrangements shown in Figs. 2 to 5, where the springs are duplex in character.

The member B, which I term the "fulcrum-spring," is curved upward at each end and attached to the body A, the member C attached at its center N to the center portion of the fulcrum-spring, and is hinged or otherwise secured to the side bars, E, at the ends L, or it may be secured to the bolster and rear axle if used as a side spring. When the body of the vehicle is loaded the weight is sustained at the five points D, D, L, L, and N, and as the weight is increased the spaces K K, between the fulcrum and the main springs B C, are closed correspondingly, the bearing of the upper member is extended, and a proportionately greater resistance offered as the load increases or descends. By this means the upper and lower members of the springs automatically adjust themselves to the weight imposed. The member B serves thus in the double capacity of a supplemental spring and as a fulcrum on which

the lower spring, C, acts as a lever. The fulcrum-spring B will, of course, have a limited spring-action of its own independent of the lower member.

5 In Figs. 4 and 5 is represented a modification. The members are divided centrally between their outer bearings, the ends arranged side by side and united by a bolt in such manner as to form an operative joint, the members 10 in other respects being constructed and attached to the body and the frame of the gear, as before described. As the weight is applied to the body A the joint N' is carried down, by the lever-like action of the lower member, in 15 the direction of the arrow H', and the spaces between the springs indicated by arrows K K are closed, as before described; but in this case it is best to make the fulcrum-springs B B of heavier steel or of a greater number of 20 plates than in making the spring shown in Fig. 3.

If desirable to reduce weight, the fulcrum-springs B, Fig. 4, may be made each of a light single plate of steel, and a supplemental re- 25 acting or returning spring may be interposed in such manner as will tend to restore the joint N' to its normal position, as well as to give support to the fulcrum-springs. (See dotted lines, Fig. 4.) If preferred, the joint N' may be 30 formed by milling out one-half of each eye where the two are in contact, and thus halve the eyes together and bring the divided springs on a line with each other, in place of placing them side by side, as now seen in Fig. 5. It 35 will now be seen that in addition to these springs automatically adjusting themselves to the weight imposed, their central connection will further compel a unity of action of all of the members, causing them to adjust them- 40 selves to carry the body level when loaded more on one side than the other; for, when one side is depressed the central joint or connection is also carried down, taking with it in its vertical movement the springs on the op- 45 posite side, and thus compels an almost perfectly level movement of both sides of the body, and prevents its side or tilting motion.

The other part of my invention relates to a fastening for the meeting side bars of the 50 frame.

A blind-clip, J, Fig. 7, is formed with a hole, I, in the top, and with terminating fingers J' J'. The front end of one bar—as, for instance, side bar, E—is placed in position on the end of

the other bar—say a bolster, F, Fig. 6. Holes 55 are bored on each side of the bar F to receive the fingers of the clip J, which is now placed on the top of the bar with its fingers in the holes. The whole is firmly and rigidly held together by a bolt, I², passing vertically through 60 the clip-opening I and through both bars, and united or secured by a nut at either end. This bolt I² may also hold the end of an under brace, R, secured at the other end to the bar E at the rear of the clip J. A strong, cheap, 65 and neat connection is thus secured.

Without limiting myself to the precise arrangement of parts shown,

I claim—

1. A spring-support for the bodies of vehicles 70 and other platforms, consisting of two flexion members arranged one over the other, the outer end or ends of the upper member being attached to the bottom of the body and curved upward toward the latter at the center, the 75 outer end or ends of the lower member being attached to the side bars or other support, and the said members converging and being united at their inner portions, substantially as and for the purpose set forth.

2. A spring-platform in which a lower spring member secured to a side bar or other support at the outer end is attached at the inner portion to the free portion or end of an upper spring member, the other end of which is connected to the body, both portions being curved upward toward the center of the body, substantially as set forth.

3. The combination, with the fulcrum-spring B and main supporting-spring C, centrally 90 united between their outer bearings by a hinged joint, N', of the supplemental spring P, substantially as and for the purpose set forth.

4. The combination, with the meeting-bars of the frame, of a clip passing over the top of 95 one bar and having fingers extending into the openings in the other bar, a bolt or rivet passing up vertically through both bars and clip, substantially as and for the purpose set forth.

5. The combination of the cross-bars, clip-bolt, and brace R, substantially as set forth.

In testimony whereof I have signed my name to this specification in the presence of two subscribing witnesses.

CYRUS W. SALADEE.
